UNITED STATES PATENT OFFICE

SAMUEL P. RUFF, JR., OF BOWLING GREEN, NETHER PROVIDENCE TOWNSHIP, PENNSYLVANIA, ASSIGNOR TO ABERFOYLE MANUFACTURING COMPANY, OF CHESTER, PENNSYLVANIA, A CORPORATION OF PENNSYLVANIA

PROCESS OF TREATING YARN

No Drawing.

Application filed January 13, 1930. Serial No. 420,598.

This invention relates to the process of treating yarn which is used commercially for knitting and the like.

Before knitting yarn into fabrics, the 5 yarn is, in most cases, treated by subjecting the same to the influence of oils, etc., which soften and condition the same.

In this condition, the yarn is wound onto a cone, spool or other package, and delivered 10 to the knitter for knitting into fabrics.

In any room or department where numerous persons are employed there is likely to be at certain times of the years, a prevalence of coughs, colds, etc., leading to sickness, with the consequent loss of time by the employee which results in loss of wages to him and additional cost to the manufacturer. This cost can be reduced by a preventive measure.

20 When a yarn manufacturer or processor has sold yarn to the knitter, its identity oftentimes becomes lost, when mixed with the yarns purchased from other concerns, and, therefore, it becomes a problem to determine 25 from which manufacturer or processor the particular yarn was purchased. This is particularly true where uncolored yarns are processed and sold and are then dyed by the knitter.

30 This invention has for its object the treatment of yarn so as to improve the health conditions in the knitting mill, and to provide the yarn with a positive means of identification, even after the same has passed 35 from the hands of the knitter.

Yarn, before being wound onto the package, in which form the same is sold, is usually treated for conditioning and softening the same with an emulsion consisting 40 of pure water (aqua), vegetable oil, such for instance, as cocoanut oil and soap. The finished package of yarn retains a percentage of the emulsion, which is largely evaporated during the knitting process.

45 In my invention I add to the emulsion compound approximately 5% in volume of pine oil, which is beneficial to the human respiratory system and acts as a preventive for coughs, colds, etc.

50 In the ordinary practice, the treatment of

the yarn takes place as the same is being wound into packages and as a further step in my invention, after the yarn has been treated with the emulsifying liquid consisting of the aqua, vegetable oil, pine oil and soap, perfume of a distinctive odor is directed onto the yarn strand by means of an atomizer.

From a theoretical standpoint, the perfume might just as readily be added to the 60 emulsifying liquid, but on account of the high cost of a distinctive and lingering perfume, I find that it is best to add the same with the atomizer, using approximately 2 c. c. of perfume to approximately 1½ lbs. of 65 yarn.

The price of this quantity of perfume is not prohibitive and answers all the purposes for which it is intended.

In the knitting of yarn in the fabric, the 70 pine oil is thrown off into the atmosphere and provides a healthy condition for the workers, but the pine oil quickly evaporates when freed from the wound package and by the time the garment has been knitted, the 75 odor of pine oil has almost entirely disappeared, but the perfume which has, as before explained been directed by an atomizer onto the yarn, gives off a pleasant odor which in the case of dyed yarn, it retains 80 long after it leaves the knitter and is placed on the retailers' counter.

The purpose of using the perfume is two-fold. First, it gives the garment a dainty and clean odor which enhances sales and, 85 second, but most important, it provides a means of identification as to the source of the yarn used for said garment.

In knitting mills, yarns from different sources are oft times confused and credit is 90 often claimed of one concern for defective yarn when, as a matter of fact, the defective yarn may have been purchased from another concern.

The perfume which I use is one which is 95 distinctive and can be purchased from the manufacturer by no other person or concern. The yarn, therefore, can be definitely traced by the perfume which it exhales. As an example, some yarns are purchased in 100

undyed, but treated, condition and are then dyed by the knitter. If, for instance, the yarn does not dye properly, a sample of the knit fabric consisting of yarn as sold to the customer can then be scientifically dyed by the seller, so that if the results obtained are good, it is at once apparent that the fault has been with the knitter on account of improper dyeing. If defective fabric should be returned to the seller he can at once determine by the distinctive odor whether he did or did not sell the yarn contained in the fabric.

It, therefore, follows that the perfume 15 readily traced through the various stages of the manufacture of the yarn into fabric can be positively identified at any time by the seller of the same so that unjust claims for adjustments will be eliminated.

20 While I have specified an improved process for conditioning and softening yarn, it will be at once apparent that various modifications and changes in the quantities of ingredients, point of introduction of the various ingredients, etc., may be modified and changed in many ways without departing from the invention herein set forth and hereafter claimed.

25 The invention is hereby claimed as follows:

30 A yarn package characterized by an identifying odor provided by an odoriferous compound evenly distributed throughout the yarn strand.

35 In testimony whereof I have signed my name to this specification.
